FLOOR MAT

Anthony Sobolewsky, Passaic, N. J., assignor to
United States Rubber Company, New York,
N. Y., a corporation of New Jersey

Application May 21, 1951, Serial No. 15,271

Term of patent 14 years

(Cl. D9—6)

To all whom it may concern:

Be it known that I, Anthony Sobolewsky, a citizen of the United States, residing at Passaic, in the county of Passaic and State of New Jersey, have invented a new, original, and ornamental Design for a Floor Mat, of which the following is a specification, reference being had to the accompanying drawing, forming part thereof.

Fig. 1 is a perspective view of the top surface of a floor mat, showing my new design.

Fig. 2 is an enlarged perspective view of a portion of the top surface of the floor mat of Fig. 1, and showing a cross section thereof taken on the line 2—2 of Fig. 1.

I claim:

The ornamental design for a floor mat, as shown.

ANTHONY SOBOLEWSKY.
